UNITED STATES PATENT OFFICE.

LOUIS F. McCLEERNAN AND JAMES McCLEERNAN, OF CHICAGO, ILLINOIS.

DESIGN FOR A SHEET-METAL KITCHEN-CABINET.

45,285.

Specification for Design.

Patented Feb. 10, 1914.

Application filed October 10, 1913. Serial No. 794,521. Term of patent 7 years.

To all whom it may concern:

Be it known that we, LOUIS F. McCLEERNAN and JAMES McCLEERNAN, citizens of the United States, residing at Chicago, in the county of Cook and the State of Illinois, have invented a new, original, and ornamental Design for Sheet-Metal Kitchen-Cabinets, reference being had to the accompanying drawing, forming a part thereof.

The figure is a perspective view of a kitchen cabinet showing the new design.

We claim—

The ornamental design for a sheet metal kitchen cabinet, as shown.

L. F. McCLEERNAN.
JAMES McCLEERNAN.
